United States Patent Office

Des. 196,454
Patented Oct. 1, 1963

196,454

BOTTLE

Edward J. Stengle, Jr., Toledo, Ohio, assignor to Owens-Illinois Glass Company, Toledo, Ohio, a corporation of Ohio

Filed June 4, 1962, Ser. No. 70,406

Term of patent 14 years

(Cl. D58—8)

FIG. 1

The dominant features of my design reside in the portions shown in full lines.

I claim:

The ornamental design for a bottle, substantially as shown and described.
